UNITED STATES PATENT OFFICE

CARL M. PETERSEN, OF TRENTON, NEW JERSEY, ASSIGNOR TO CIRCLE F MFG. CO., OF TRENTON, NEW JERSEY, A CORPORATION OF NEW JERSEY

ELECTRIC CONNECTER

Application filed October 8, 1928. Serial No. 311,145.

This invention relates to improvements in electric connectors and more particularly to a novel body or shell construction which may be readily embodied in various forms 5 such as a switch socket having a side outlet, and ordinary switch sockets.

A primary object of the invention is to provide an electric connector of the molded fibre type embodying novel features of construction which assist materially in the manufacture and assembly of a high class device 10 of simple construction and one which is pleasing in appearance.

A further object of the invention is to 15 provide an electric connector including a simplified body structure and unique mounting means for the mechanism housed therein.

With the above and other objects in view which will more readily appear as the nature 20 of the invention is better understood, the same consists in the novel construction, combination and arrangement of parts herein-after more fully described, illustrated and claimed.

25 A preferred and practical embodiment of the invention is shown in the accompanying drawings in which:

Figure 1 is a side elevational view of an electric connector embodying this invention.

30 Fig. 2 is a similar view to Figure 1 but taken substantially at right angles thereto.

Fig. 3 is a longitudinal sectional view taken upon line 3—3 of Fig. 4.

Fig. 4 is a longitudinal sectional view taken 35 on line 4—4 of Fig. 3.

Fig. 5 is a fragmentary longitudinal sectional view of a slightly modified form of connector.

Similar reference characters designate cor- 40 responding parts throughout the several figures of the drawings.

According to the embodiment of the invention shown in the accompanying drawings, the invention includes an insulated housing shell or body formed by two mating portions or sections A and B that are preferably molded from a suitable plastic insulating material, such as bakelite. These sections meet in a plane parallel to and intersecting the longitudinal axis of the connector and are held to-

gether at one end by the screw-ring C and near the other end by the fastening E. As will hereinafter more fully appear, all of the electrical parts of the device may be assembled on one of the sections and the other then applied thereto. The sections may then be secured together by the ring C and the single fastening E which makes the final assembly simple and expeditious, thus greatly enhancing the value of the improved construction from a manufacturing standpoint. 55

The hollow sections A and B, when assembled, provide a boss 13 at one end, a socket 14 at the other end, and a side outlet 15. The plane or dividing line between the sections intersects the boss, the socket, and the side outlet in the manner best illustrated in Figs. 2 and 4. The socket 14 is defined at its inner end by a partition 16 and from the partition to the extremity of the boss 13 the body is hollow to form a chamber 17. Fig. 4 discloses the section B of the body as having a portion of its inner wall which defines the chamber 17 increased in thickness at 18 to act as an anchorage or mounting for the mechanism 60 housed within the body. 70

By way of example, a pull chain switch mechanism is illustrated in the present construction, the same being mounted within the chamber 17 and including a shaft 19 permanently anchored to the thickened wall portion 18. Rotatable about the shaft 19 is an insulating block 20 carrying movable contact members illustrated generally at 21. An operator plate 22 also is rotatably mounted 75 upon the shaft 19 and is connected to the insulating block 20 by a suitable one-way clutch mechanism, not shown. For returning the plate 22 to its starting position after each operation, a spring 23 encircles the outer end 80 of the shaft and has one end anchored at 24 to the plate 22 and its remaining end adjustably connected at 25 to a washer 26. This washer is provided with a circular series of 85 axially extending lugs 27 and the end 25 of the spring may be adjusted with respect to these lugs for varying the tension of the spring. The washer 26 is non-rotatably connected to the end of the shaft 19. For the purpose of rotating the insulating block 20 90

with its contact members 21, a flexible operator or pull chain 28 is connected to an extension 29 formed on the plate 22. This pull chain 28 passes outwardly of the chamber 17 through a chain guide or bell 29a which is formed in the engaging faces of the sections A and B.

The exterior surfaces of the portions of the body forming the boss 13 are formed with a 10 screw thread for meshing with the interior thread formed on the screw-ring C. This ring encircles the portions of the body forming the boss 13 and assists in retaining the portions in their proper assembled position. 15 To secure the ring in place, that is, against unscrewing movement, the outer flange thereof is bent down as shown at c' in Fig. 4 into the notches 13a.

The screw shell 31 is adapted to be mounted 20 in the socket portion 14 of the assembled body, as best illustrated in Figs. 3 and 4. For the purpose of mounting this shell 31 by the act of assembling the body sections A and B, the latter are provided with lugs 32 which 25 preferably are diametrically opposed, and the shell is provided with registering apertures 33 for receiving the lugs.

The side outlet 15, as stated heretofore, is formed by suitably shaped projections carried by the body sections A and B. Openings 34 are formed in the end face of this side outlet 15 for receiving the blades of a plug 35 of the type illustrated in dotted lines in Fig. 1. The outlet 15 is provided with the 35 plug terminal receiving recesses 36, which register with the openings 34, and the inside face or wall of the section B is provided with the ribs 36a and 36b whose functions will presently appear.

40 An opening 37 is formed partly in each of the end faces of the sections A and B which occur at the extremity of the boss 13. This opening accommodates the ribbon-like conductor 38 which is bent over at its outer end 38a to form a contact. The inner end of the conductor is anchored at 39 to the thickened wall portion 18 and is connected by the anchoring means to the stationary contact 40 which forms a part of the pull chain switch 45 mechanism. A second contact 41 is connected to anchoring means 42 which likewise is carried by the thickened wall portion 18. This anchoring means 42 connects to the switch contact 41 a center contact 43 located 50 within the screw shell 31. The male ring C electrically contacts with a conductor spring 44 which extends lengthwise through the chamber 17 and around the rib 36a to be connected by a rivet or the like 45 to the screw shell 31. The end of the conductor 44, beyond the rivet 45, is provided with a return bend 46 to form a plug terminal contact 47 arranged within the recess 36 in line with one of the openings 34. Another conductor 55 spring 48 has one end passing through the

opening 37 and is bent at an angle to form a contact 48a similar to the contact 38a. This conductor 48 also extends through the chamber 17 and its intermediate part is clamped against the wall 36b while the other end is doubled upon itself to provide another plug terminal finger disposed in the other of the recesses 36. The sections A and B, after the switch mechanism and the various conductors and shells are arranged in their proper places, may be further connected by an eyelet E passing through apertured ears 15a formed in the manner illustrated in Figs. 1 to 3, inclusive.

It now will be seen that the connector may be threaded into an ordinary light socket by means of the boss 13 and its encircling ring C. The circuit for the female shell 31 will be controlled by the pull chain switch mechanism illustrated. The contacts 47 and 49 registering with the openings 34 in the side outlet will be free from all control by the said switch mechanism. The connector will permit of a bulb being threaded into the shell 31 and controlled by the pull chain switch mechanism while a lamp cord, or the like, may be connected to the side outlet and be provided with a closed circuit irrespective of the condition of the pull chain switch mechanism.

Figure 5 illustrates a slightly modified form of connector in which the boss 13 is dispensed with and a cap or equivalent annular or ring like member 50 is threadedly connected with the separate portions forming the body 10a. This cap 50 is provided with an opening 51 for accommodating the wires 52 which are connected by screws 53 to the conductors 38, 44 and 48 of the mechanism disclosed in Figs. 3 and 4.

The pull chain switch mechanism in the structure shown in Figure 5 may be the same as illustrated in Figs. 3 and 4. A female screw shell and a side outlet similar to those illustrated in Figs. 3 and 4 also may be provided to complete the structure illustrated in Fig. 5.

From the foregoing it will be apparent that the present construction includes in its organization a pair of complementary longitudinal body forming sections A and B, the latter serving principally as a mechanism supporting base, and the former constituting a cover, and both being joined at one end by an annular member or ring which may be threaded to engage both sections, while a single fastening locks both members near the opposite end against slippage or separation. In assembling the device the body section B may have the pull chain switch mechanism assembled thereon, as well as the center plug contact 43 of the screw shell 31, together with the contact 38-38a for the plug end of the device. The spring conductor member 44 which is carried by the screw shell contact 31 may then

be placed in position so that the end 44a lies in recess 44b while the bent terminal finger 47 for one of the blades of the push-plug, lies in one of the recesses 36, and the screw shell itself engages over one of the lugs 32. 5 The other spring conductor member 48 may then be fitted into the space between the rib 36b and the body so that the end 48a thereof forms a part of the center contact for the 10 plug end of the device while the portion 49 lying within the other of the recesses 36 constitutes the second push-plug terminal. When the various parts are assembled, the 15 cover section A may be placed in position and the screw threaded ring C may be threaded onto the threaded end portions of the sections A and B to hold them together and at the same time make an electrical connection between the ring C and the end 44a of the 20 spring contact member 44. When the rivet, eyelet or equivalent fastening E is placed through the aperture ears 15a, the entire assembly will be held in place to complete the device. The lugs 32 which enter the openings 25 33 in the screw shell contact not only hold that member in place but also prevent its rotation during the screwing in and out of the lamp bulb, and take the strain off of the connection between the screw shell and the 30 conductor to which it is attached.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:

40 1. An electrical connector, including longitudinal complemental housing-shell sections of molded insulating material, a socket formed at one end of said members, a screw shell contact within the socket, a center contact within the screw shell, said housing shell having a side outlet, side outlet terminals arranged in said side outlet, a conductor for one of said terminals connected with the 45 screw shell, a ring carried by one end of the housing shell sections and electrically connected with said last named conductor, the other of said side outlet terminals including a conductor portion passing through the end 50 of the plug portion of the device and constituting a center contact thereof, an electrical connection between the center contact of the said plug portion of the device and the center contact of the socket independent of 55 the connection of either of said side outlet terminals with the plug portion of the device, and a pull switch arranged in said last named connection.

2. A combination pull chain socket and 60 current tap connector including a pair of

complemental longitudinally matched housing-shell sections of molded insulating material, said housing-shell provided at one end with a plug part, at its opposite end with a lamp socket, and at the side with a current 70 tap side outlet, a screw shell and a center contact within the lamp socket part of the housing-shell sections, a contact ring and a center contact carried by the plug part of the housing-shell and coaxial with the lamp socket screw shell and center contact, respectively, a pull chain switch mounted within the housing-shell in circuit controlling relation to said center contacts, and contact elements 75 for the current tap side outlet which are separate and independent from the switch and are directly and permanently connected to the plug contact ring and center contact, respectively.

3. A multiple tap socket comprising a longitudinal split insulating housing of matching sections formed with an enclosed intermediate switch chamber with enclosed side outlet chambers, and with partition walls at the side of the switch chamber having registering conductor grooves, said housing being also formed at one end with an attaching plug having main wire line terminals, and at its opposite end with a lamp socket having lamp terminals, a pull switch 90 mechanism enclosed in the switch chamber, switch contacts connecting respectively with a plug terminal and with a lamp terminal, side outlet plug contacts each separately housed in one of the side outlet chambers and each having a metal conductor connecting with one of the plug contacts and clamped by the housing sections within one of said conductor grooves, one of said metal conductors 95 having a metallic connection with one of said lamp terminals.

4. A multiple tap socket comprising a longitudinal split insulating housing of matching sections formed with an enclosed intermediate switch chamber and interior side outlet chambers, said housing being also formed at one end with an attaching plug having main wire line terminals and at its opposite end with a socket having a screw shell and a center contact, a pull switch mechanism in 110 the switch chamber, switch contact elements connected respectively with a plug terminal and with the center plug contact of the lamp socket, side outlet contacts housed in the side outlet chambers, and a pair of metal conductors within the housing both located entirely at one side of the switch mechanism, one of said conductors connecting a side contact with one of the terminals of the attaching plug and the other being connected directly with the said screw shell and another of the terminals of the attaching plug.

In testimony whereof I hereunto affix my signature.

CARL M. PETERSEN. 130
